UNITED STATES PATENT OFFICE.

ALBERT MILLER AND JACOB DIRSCHAUER, OF EVANSVILLE, INDIANA.

JAR WRENCH.

Application filed September 14, 1925. Serial No. 56,304.

This invention relates to wrenches for applying and removing the screw caps of fruit jars.

Our object is to provide a simple, durable, compact and efficient wrench of improved construction which can be held in the hand and quickly and easily operated to screw up tightly, or to unscrew, the screw cap of a fruit jar.

The principle of the invention resides in concentric relatively rotatable or turnable rings, gripping jaws and cam surfaces to cooperate therewith to project, and cams to retract the jaws when the rings are relatively rotated, and in other features and improvements appearing more fully herein-after.

A practical embodiment of the invention is shown in the drawings and hereinafter described, but we wish it to be understood that the invention is susceptible of modification from the form shown and described, without departing from the principle of the invention.

In the accompanying drawing—

Figure 1 is a top view;

Fig. 2 is a bottom view;

Fig. 3 is a top view with the body removed, certain parts being in section;

Fig. 4 is an edge view showing the jaws and their springs;

Fig. 5 is a vertical section; and

Fig. 6 is a side view showing the wrench in use on the cap of a fruit jar.

The wrench has a body 1 and a retaining ring 2, there being provided cam notches 3 in the retaining ring, said notches having shoulders 4.

Concentrically arranged within the retaining ring and body and mounted to turn therein, is an operating ring 5 which is provided with radial slots 6, one of whose walls 7, or both of them, may be of the form shown, providing a fulcrum or fulcrums 8.

Slidably mounted in the openings 6 and adapted to pivot or fulcrum on the fulcrum or fulcrums 8 are jaws 9 whose inner ends 10 are provided with teeth and whose outer ends are beveled at 11, the outer ends being adapted for reception in the notches 3. The beveled ends 11 may slide against the cams of the notches for the purpose of projecting the jaws 9 inwardly to exert a gripping action on the fruit jar cap when the retaining ring 2 is turned in a clockwise direction; when said ring is turned in the opposite

direction in relation to the ring 5, the beveled ends of the jaws may snap into the said notches and by engagement with the shoulders 4 be rocked on the fulcrum 8 to release them from the jar cap.

If the other fulcrum 8 is provided, not only will the jaws be bodily projected toward the jar cap but the rocking action exerted on the jaws will more firmly wedge them against the said cap.

Each jaw is retracted outwardly, so that it is adapted to snap into the cam notch 3 if the ring 2 is rotated in a counter clockwise direction by its own spring 12, said spring being a curved leaf spring engaged with the jaw and anchored in the ring 5 and movable in a slot 13 therein.

Contained within the body 1 is a metal disk 14 and a rubber disk or rubber fabric or other suitable material disk 15 which bears on the ring 5. A screw 16 threaded through the body 1 and having its tip engaged with the metal disk 14 enables any desired pressure to be exerted on the disks 14 and 15 to hold them pressed inwardly.

The body has finger notches or grips 17 to enable the user to hold the wrench in his hand and to manipulate it without slippage.

A fruit jar is shown at 18 as provided with a screw cap 19, and the wrench applied thereto in Fig. 6 to illustrate the manner of use.

On turning the body 1 and ring 2 in a clockwise direction, the jaws 9 are forced inwardly by the cam bottoms of the notches 3, causing the jaws to bite on the cap 19 which may then be tightly screwed on the jar. On reversing the direction of turning motion applied to the body 1 and ring 2, the jaws are released.

What we claim is:

1. In a wrench for screw caps, the combination of an outer body adapted to be turned by the operator, an inner operating ring having an opening to receive the screw cap which is to be manipulated, rockable jaws slidably mounted in the inner ring, springs for retracting said jaws, and cam surfaces on the outer body adapted to engage said jaws to press them inwardly when said body is turned in one direction and permitting the springs to retract said jaws when the body is turned in the opposite direction.

2. In a wrench for screw caps, the combination with an outer body adapted to be

turned by the operator, of an inner operating ring having an opening to receive the screw cap which is to be manipulated, said ring being rotarily mounted inside of the body and having openings provided with fulcrums, jaws slideable and rockable in said openings and adapted to rock on said fulcrums, the inner ends of the jaws being adapted to project into the aforesaid opening or to be retracted, and means on the outer body for operating said jaws.

3. In a wrench for screw caps, the combination with an outer body adapted to be turned by the operator, of an inner operating ring having an opening to receive the screw cap which is to be manipulated, said

ring being rotarily mounted inside of the body and having openings provided with fulcrums, jaws slideable and rockable in said openings and adapted to rock on said fulcrums, the inner ends of the jaws being adapted to project into the aforesaid opening or to be retracted, said outer body being provided with cam notches and shoulders to cooperate with the outer ends of the jaws, and springs carried by the inner ring which are adapted to retract said jaws. 20 25

In testimony whereof we affix our signatures.

ALBERT MILLER.
JACOB DIRSCHAUER.
